UNITED STATES PATENT OFFICE

SEYMOUR W. FERRIS, OF PHILADELPHIA, PENNSYLVANIA, ASSIGNOR TO THE ATLANTIC REFINING COMPANY, OF PHILADELPHIA, PENNSYLVANIA, A CORPORATION OF PENNSYLVANIA

FRACTIONAL EXTRACTION OF MINERAL OILS

No Drawing.

Application filed July 16, 1927. Serial No. 206,388.

My invention relates to the art of mineral oil refining, with particular reference to the separation of crude petroleum or petroleum products into fractions of different chemical compositions while of approximately the same distillation range.

In accordance with my invention crude petroleum or petroleum products, particularly oils of substantial viscosity, are separated into various fractions by means of fractional extraction with an aromatic nitro-compound.

Petroleum is essentially a mixture of hydrocarbons comprising numerous groups or homologous series of these compounds such as the paraffins of general formula C_nH_{2n+2} , the olefins C_nH_{2n} , the hydro-aromatics and the polymethylenes of the same empirical formula, and various other series in which the hydrogen to carbon ratio is even lower than in these and some of which have a chain structure and some a ring structure. A large number of individual hydrocarbons of each series are present and have different boiling points.

In the various types of crude petroleum commonly known as paraffin base, naphthenic or asphalt base, and mixed base these various series of hydrocarbons are present in different proportions. For example, in the paraffin base crudes such as those from the Appalachian field there is a relatively high proportion of the hydrocarbons having a chain structure and a high hydrogen to carbon ratio, whereas in the so-called naphthenic crudes there is a relatively high proportion of hydrocarbons of the ring structures and lower hydrogen to carbon ratio. The mixed base crudes such as those from the Mid Continent area are intermediate between these two extreme cases.

In the normal refining processes for crude petroleum, the fractions of varying distillation ranges which are successively obtained in distillation of the oils partake of the general character of the crude; for example, lubricating oils from Appalachian crudes will show paraffinic characteristics whereas the oils from the naphthenic crudes show naphthenic characteristics. The physical properties of the resultant oils are dependent in this

way upon the chemical composition of the crude oils from which they are derived. For the same distillation range, a paraffinic oil will show a lower viscosity, a lower specific gravity, and a lower refractive index than a naphthenic oil.

Similarly a paraffinic oil of a given viscosity will show a lower specific gravity and refractive index and a higher flash test than a naphthenic oil of the same viscosity. The viscosity-gravity relationship offers a very good criterion of the chemical character of the oil and for each crude there may be plotted from the properties of the fractions obtained by normal distillation, a curve showing the viscosity against the specific gravity. The position of this curve is typical of the crude and of the oils which may be produced from it by processes heretofore well-known. For example, an oil of 80 seconds Saybolt universal viscosity at 210° F. from a certain Pennsylvania crude has a specific gravity of 0.885 whereas an oil of the same viscosity from a typical Gulf Coast crude has a specific gravity of 0.943. These relationships are fully discussed in Hill and Ferris, Industrial and Engineering Chemistry, vol. 17, page 1250 (1925).

Hence, if a fraction obtained by distillation, for example from a Mid-Continent crude, be subjected to an extraction and separation in accordance with my invention hereinafter set forth more in detail, the extract resulting, upon separation into a number of fractions by distillation, and upon determination of the specific gravities and viscosities of said fractions and plotting said specific gravities as ordinates and said viscosities as abscissæ and drawing a curve through the points so plotted, the extract will be characterized by said curve. Furthermore, such curve will be found to lie definitely above a curve similarly plotted for similar data obtained upon the starting material before extraction, that is to say, a fraction of the extract having a given viscosity will have a greater specific gravity than the specific gravity of a fraction of the starting material of the same viscosity; and in accordance with the terminology used herein and in the ap-

pended claims, such extract is referred to as one "richer in naphthenic" hydrocarbons or compounds. The undissolved fraction, or that fraction remaining after extraction and separation as aforesaid, may also be represented by a curve plotted from similarly obtained data, which curve will fall definitely below the curve characteristic of the starting material before extraction; and in accordance with the terminology of this application and of the appended claims such fraction is referred to as one "richer in paraffinic" hydrocarbons or compounds.

When the properties characteristic of naphthenic oils were desired, heretofore it has been necessary to obtain such oils from a naphthenic crude, whereas on the other hand where paraffinic properties were desired, it has been necessary to start with a paraffinic crude. On account of certain qualities of the oils produced, the paraffinic crudes have long been at a premium since even with a mixed base crude of relatively high paraffinic characteristics the oils produced have been somewhat more naphthenic than those from the straight paraffin base crudes and have, therefore, been less desirable for certain purposes.

I have found that oils containing both the paraffinic series of hydrocarbons and the various naphthenic series may be fractionally extracted with a suitable solvent such as a nitro derivative of an aromatic hydrocarbon, and more particularly nitrobenzene. The various series of hydrocarbons possess a differential solubility in this solvent, the naphthenic compounds being much more soluble than the paraffinic hydrocarbons. By means of extraction with nitrobenzene, it is, therefore, possible to effect a partial separation of the naphthenic compounds from the paraffinic and to obtain from an oil containing both classes an oil which is much more paraffinic than the original and one which is much more naphthenic. By my invention, for example, it is possible to produce an oil of the quality normally obtained from Appalachian crudes from crudes of the mixed base type from the Mid Continent area and, conversely, to obtain oils from mixed base crudes such as are normally obtained from the naphthenic oils from the Gulf Coast area.

In practicing my invention, I prefer to mix the oil fraction to be treated with a suitable proportion of nitrobenzene at elevated temperatures so that complete solution is effected and a homogeneous liquid obtained. I then cool the mixture and produce a separation into two layers, the upper one of which is a solution of nitrobenzene in the more paraffinic portion of the oil and the lower layer of which is a solution of the more naphthenic portion of the oil in nitrobenzene. Instead of this heating and cooling I may also simply agitate the cold mixture. Where large quantities of solid hydrocarbons are present

which may belong to the true paraffin series C_nH_{2n+2} , these solids or waxes remain in the upper layer and may cause it to be solid or semi-solid. I then effect separation of the two layers by decantation or other means and remove the nitrobenzene from each of the separated oil layers by distillation or other means, obtaining thereby two oils of similar distillation ranges but of widely different physical characteristics and correspondingly different chemical compositions.

Before removing the nitrobenzene from the upper layer obtained in the above described process, I may add a further quantity of nitrobenzene and repeat the process for an extraction of further naphthenic bodies from the oil. The extraction may be so repeated two or three times, or as often as desired. In wax-bearing oils, the finally extracted product so obtained is a mixture of solid and liquid hydrocarbons. While the exact chemical compositions of these compounds are not known, it is probably the fact that the liquid hydrocarbons are branched chain hydrocarbons of the paraffin series whereas the solid bodies are straight chain paraffin hydrocarbons. This product may be further separated into solid and liquid hydrocarbons by any of the well-known dewaxing processes, such as the cold settling process in which the oil is diluted with naphtha, chilled, the solid hydrocarbons allowed to settle, the clear supernatant liquid decanted off, and the naphtha removed from both portions by distillation.

As an example of my process, there is described below the treatment of a high viscosity wax-bearing distillate obtained from a typical Texas mixed base crude with the production of oil fractions of a naphthenic character, an oil fraction of a paraffinic character, and a solid wax. To an oil of the aforesaid source having a viscosity of 90 seconds Saybolt universal at 210° F. and a specific gravity of .9156 at 15° C., I may add a quantity of nitrobenzene in the proportion of about two gallons per gallon of oil. The mixture is heated to about 60° C. and agitated until solution is effected. The oil is then cooled with gentle agitation to about 10° C. and agitation is discontinued, whereby a two layer system is formed. The lower or nitrobenzene layer is drawn off and freed from nitrobenzene, as by distillation with steam under reduced pressure.

The upper layer, which is semi-solid due to the concentration in it of the major portion of the solid wax, is again treated with nitrobenzene as above and separated into two layers and this process is again repeated for the third time. The two additional nitrobenzene extracts, after removal of the nitrobenzene by distillation, furnish two additional oil fractions somewhat less naphthenic,

however, than that obtained from the first extraction.

The upper layer from the final extraction is diluted with naphtha, chilled to about 5 minus 20° C. and allowed to stand in order to effect a final separation of the wax from the residual oil. The clear supernatant naphtha is then removed from the lower wax layer and the naphtha separated from both 10 portions by distillation.

The properties of the various fractions obtained are shown in the table below:

	Vis. Say-bolt univ. @ 210° F.	Specific gravity @ 60° F. (actual)	Specific gravity @ 60° F. (calculated)
Original oil	89.8	0.9168	
Dissolved oil from extraction #1	148.2	0.9603	0.928
Dissolved oil from extraction #2	96.4	0.9262	0.916
Dissolved oil from extraction #3	74.0	0.8997	0.911
Undissolved oil (dewaxed)	69.0	0.8707	0.910

A different chemical composition of the fractions is shown by the difference between 25 the actual specific gravities and the "calculated" specific gravities of the oils produced by these extractions. This latter column indicates the specific gravity corresponding to the viscosity if the oil had been obtained 30 from the crude from which the original oil was produced, by normal distillation and refining processes. Thus, on extracted fraction #1, which is the oil obtained from the nitrobenzene layer from the first extraction, 35 the actual specific gravity is much higher than the "calculated", indicating that the fraction is much more naphthenic than would normally be produced from this type of crude. On the other hand, in the case 40 of the residual oil which is the oil portion obtained after the cold settling of the finally extracted product, the actual specific gravity is much lower than the "calculated", showing that the oil is much more paraffinic than 45 the original. The wax obtained is the high melting product such as would be obtained from such an original oil by any of the well-known processes of wax removal. It will be noted that the oils obtained by the second 50 and third extractions possess properties between the two extremes, i. e. the residue from extraction #2 has an actual specific gravity somewhat higher than the theoretical specific gravity, indicating a more naphthenic oil than ordinary distillation and refining processes would yield, while in the case of the residue from extraction #3, the actual specific gravity is less than the calculated value showing the oil to be more 55 paraffinic.

That this process is one of separation into classes rather than one of chemical reaction between the oil and the nitrobenzene is shown by the fact that upon mixing the various oil 60 fractions and the wax in the proportions in

which they were obtained from the original oil, the resultant product is the same as the original oil, as indicated by the physical properties.

While I have described my process with the 70 use of nitrobenzene as the solvent, I do not intend to limit myself to this particular compound but may use instead nitrotoluene, mono-nitro-naphthalene or other suitable nitro derivatives of an aromatic hydrocarbon. 75

It will be seen that by the use of my process I am practically independent of the particular nature of the crude sources but may produce viscous oils of any required characteristics from practically any source. 80

For example, I am able, by my process, to produce from petroleum of a mixed base type such as would, on normal batch distillation, give a residuum of a viscosity of 150 seconds Saybolt universal at 210° F. with a specific 85 gravity of .928 or more, a lubricating stock with a viscosity of 150 seconds Saybolt or more and a specific gravity not higher than .910. This latter combination of properties is typical of cylinder stocks produced from 90 Pennsylvania crude.

I find in many instances that the oils produced by my process are superior to those produced under the most favorable conditions by normal processes from selected 95 crudes.

For example, it is well-known that oils containing appreciable quantities of paraffinic constituents decompose under the action of the electric corona with the formation of 100 an amorphous solid material, commonly known as corona wax. This property is highly detrimental in oils for electrical insulating purposes. It is difficult, by normal processes, even from carefully selected crudes 105 to obtain an oil sufficiently low in paraffinic constituents to satisfactorily withstand the action of the corona. By my process, it is readily possible to produce such an oil as the nitrobenzene extract which will show no formation of corona wax on exposure to corona for the times for which such exposure is normally made. 110

The mineral oils particularly contemplated herein for treatment in accordance with my 115 process are those having a substantial viscosity, and are herein described as "viscous" when having a viscosity of 50 seconds Saybolt universal at 100° F., and upward.

For brevity in the appended claims the term "nitrobenzene" is employed in a generic sense to include that material and equivalent aromatic nitro compounds or mixtures of them. 120

By fractional extraction in the appended claims I mean the process of contacting the material to be extracted with one or more portions of a solvent and separating the solvent and soluble portion from the insoluble portion after each contacting. 125

Herein, while I have discussed the theories which I believe underlie my invention, it is to be understood that I do not intend to be held thereto, and that my invention concerns actual physical phenomena, and is in no way predicated upon the correctness of said theories.

Furthermore, it is to be understood that the results attained by my process do not depend upon the presence in the oil to be treated of paraffins, solid at ordinary temperatures, commonly known as wax. If present, such paraffins may be removed either before the oil is subjected to my process, or if desired, from the fraction or fractions containing them after such treatment, as for example, by the well-known cold settling process. If the latter procedure is resorted to, the substantially dewaxed extract will be found to be richer in naphthenic hydrocarbons or compounds than the similarly dewaxed original oil without extraction, while the dewaxed undissolved oil will be found to be richer in paraffinic hydrocarbons or compounds than said dewaxed original oil. It will therefore be seen that my process is adapted to the treatment of wax-free oils as well as wax-containing oils.

What I claim is:

- 30 1. In the art of refining mineral oils the process which comprises bringing a viscous oil containing paraffin and naphthenic hydrocarbons into contact with nitrobenzene, thereby effecting solution of a portion of the oil richer in naphthenic hydrocarbons in the nitrobenzene, separating the nitrobenzene solution of oil from the oil so treated, and removing the nitrobenzene from each of the fractions so obtained.
- 40 2. The process of separating mineral oils into fractions which comprises bringing a viscous oil containing paraffin and naphthenic hydrocarbons into contact with nitrobenzene, thereby effecting solution of a portion of the oil richer in naphthenic hydrocarbons in the nitrobenzene, separating the nitrobenzene solution of oil from the oil so treated, and distilling the nitrobenzene from each of the fractions so obtained.
- 50 3. In the art of refining mineral oils the process which comprises bringing a viscous oil containing paraffinic and naphthenic hydrocarbons into contact with nitrobenzene, thereby effecting solution of a portion of the oil richer in naphthenic hydrocarbons in the nitrobenzene, separating the nitrobenzene solution of oil from the oil so treated, and retreating the treated oil with additional nitrobenzene.
- 60 4. In the art of refining oils the process which comprises adding nitrobenzene to viscous oil, containing paraffinic and naphthenic hydrocarbons, heating the mixture to such a temperature as to effect solution, cooling the solution to form a two layer system, and separating the upper layer from the lower layer.
- 65 5. In the art of refining mineral oils the process which comprises adding nitrobenzene to a viscous oil containing paraffinic and naphthenic hydrocarbons, heating the mixture to such a temperature as to effect solution, cooling the solution to form a two layer system, removing the lower layer, and similarly retreating the upper layer with nitrobenzene.
- 70 6. The method of producing paraffinic lubricating oil from mixed base crude which comprises distilling the crude and bringing a portion thereof into contact with nitrobenzene, thereby partially dissolving the oil, separating the nitrobenzene solution of oil from the oil so treated, and removing the nitrobenzene from the treated oil.
- 75 7. The process of producing a lubricating stock of specific gravity less than .910 and of Saybolt universal viscosity greater than 150 seconds at 210° F. from a crude petroleum which on normal distillation yields a residuum of 150 seconds viscosity at 210° F. and a specific gravity greater than .928, which comprises producing a residuum from the crude petroleum, and extracting said residuum from said crude petroleum with nitrobenzene.
- 80 8. In the art of refining mineral oils, the process which comprises separating a viscous oil containing paraffinic and naphthenic hydrocarbons into fractions respectively richer in paraffinic and naphthenic compounds by extracting said oil with nitrobenzene.
- 85 9. In the art of refining mineral oils, the process which comprises fractionally extracting a viscous oil containing paraffinic and naphthenic hydrocarbons with nitrobenzene to produce fractions of the oil respectively richer in paraffinic and naphthenic compounds.
- 90 10. In the art of refining mineral lubricating oil containing paraffinic and naphthenic hydrocarbons, the step of fractionally extracting the oil with nitrobenzene, to effect a separation of fractions respectively richer in paraffinic and naphthenic compounds.
- 95 11. The process of producing a lubricating stock of specific gravity less than .910 and of Saybolt universal viscosity greater than 150 seconds at 210° F. from a crude petroleum which on normal distillation yields a residuum of 150 seconds viscosity at 210° F. and a specific gravity greater than .928, which comprises separating a residuum from said crude petroleum and bringing such residuum into contact with nitrobenzene, to effect solution of a portion thereof with nitrobenzene, separating the nitrobenzene solution of oil from the portion which does not dissolve therein, and removing the nitrobenzene from the oil of said solution.
- 100 12. In a process for separating a viscous mineral oil containing paraffinic and naphthenic hydrocarbons into fractions which are respectively richer in naphthenic hydrocar-

bons and paraffinic hydrocarbons other than wax, the step which comprises extracting the oil with nitrobenzene.

13. In a process for separating viscous mineral oil liquid at ordinary temperature containing paraffinic and naphthenic hydrocarbons into fractions respectively richer in paraffinic and naphthenic hydrocarbons, the step which comprises extracting the oil with nitrobenzene.

14. In a process for separating a substantially wax free viscous mineral oil containing paraffinic and naphthenic hydrocarbons into fractions respectively richer in paraffinic and naphthenic hydrocarbons, the step which comprises extracting the oil with nitrobenzene.

15. The process of treating a viscous fraction of a crude oil of one type containing paraffinic and naphthenic hydrocarbons to procure a fraction having the quality of a corresponding fraction of a crude oil of different type having a greater content of paraffinic hydrocarbons, which comprises extracting the viscous fraction with nitrobenzene, and separating the oil so treated into portions respectively richer in paraffinic and naphthenic hydrocarbons.

16. The process of treating a viscous fraction of a mixed base crude oil to procure a fraction having the quality of a corresponding fraction of a paraffinic base crude, which comprises extracting the viscous fraction with nitrobenzene, and separating the oil so treated into portions respectively richer in paraffinic and naphthenic compounds.

17. In the art of refining mineral oils, the process which comprises adding nitrobenzene to a viscous oil liquid at ordinary temperatures containing paraffinic and naphthenic hydrocarbons, heating the mixture to a temperature sufficient to effect solution, cooling the solution to a temperature sufficient to form two layers respectively richer in naphthenic hydrocarbons and paraffinic hydrocarbons other than wax, and separating the upper layer richer in paraffinic hydrocarbons from the lower layer richer in naphthenic hydrocarbons.

18. In the art of refining mineral oils, the process which comprises adding nitrobenzene to a viscous oil liquid at ordinary temperatures containing paraffinic and naphthenic hydrocarbons, heating the mixture to a temperature sufficient to effect solution, cooling the solution to a temperature sufficient to form two layers, separating nitrobenzene and paraffin wax from the upper layer, and separating nitrobenzene from the lower layer to produce one fraction richer in paraffinic and a second fraction richer in naphthenic hydrocarbons than said viscous oil.

SEYMORE W. FERRIS.

CERTIFICATE OF CORRECTION.

Patent No. 1,788,569.

January 13, 1931.

SEYMOUR W. FERRIS.

It is hereby certified that error appears in the printed specification of the above numbered patent requiring correction as follows: Page 4, lines 32 and 42, claims 1 and 2 respectively, for the word "paraffin" read paraffinic; and that the said Letters Patent should be read with this correction therein that the same may conform to the record of the case in the Patent Office.

Signed and sealed this 25th day of January, A. D. 1938.
